(Cl. D1—12)

FIG. 1

FIG. 2

FIG. 3

FIG. 4

FIG. 5

FIG. 1 is a front elevational view of a rotatable illuminable advertising sign embodying our new design, the rear being substantially the same;

FIG. 2 is a side elevational view thereof, the opposite side being a mirror image thereof;

FIG. 3 is a top plan view thereof;

FIG. 4 is a front elevational view thereof with the center portion of the panel removed for convenience of illustration; and

FIG. 5 is an enlarged fragmentary perspective view of the upper portion of one corner thereof.

The broken line representation of light bulbs in FIGS. 3 and 4 are for purposes of illustration only.

We claim:

The ornamental design for a rotatable illuminable advertising sign, as shown and described.
